FIRING MECHANISM

Norman K. Turnbull, Pitman, N. J., and Herschel Smith, Southampton, Pa.

Application December 5, 1940, Serial No. 368,652

1 Claim. (Cl. 175—341)

(Granted under the act of March 3, 1883, as amended April 30, 1928; 370 O. G. 757)

The invention described herein may be manufactured and used by or for the Government for governmental purposes, without the payment to us of any royalty thereon.

This invention relates to automatic firearms generally, and in particular to a trigger motor synchronized with an aeroplane motor to permit firing between the blades of a propeller, of the general type shown in U. S. Patent No. 1,450,653.

The invention consists in a trigger motor for attachment to the side plate of a machine gun, said trigger motor having a plunger reciprocated by an electromagnet and return spring and operating in a direct line on the sear of the gun through a trip off device, and wherein the plunger is adjustable in the direction of its motion.

It is an object of the invention to provide a trigger motor for automatic firearms that will be compact and quick and dependable in operation.

It is a further object of this invention to provide a trigger motor for automatic firearms having an electromagnet plunger with adjustable position.

It is a further object of the invention to provide a trigger motor wherein the electromagnet plunger acts in a direct line on the sear.

To these and other ends, the invention consists in the construction, arrangement and combination of elements described hereinafter and pointed out in the claims forming a part of this specification.

A practical embodiment of the invention is illustrated in the accompanying drawing wherein:

Figure 1 shows a top view in axial section of the trigger motor as mounted on the left side of a gun, and

Figure 2 is a side view.

Referring to the drawing by characters of reference there is shown a base 1 of the trigger motor clamped to the side plate 2 of a machine gun by means of bolt 3 the head 4 of which nests in a conical seat in the side plate. The other end of the motor is held to the side plate in a dovetail fit as at 5.

Bolted to the base 1 and fitted on an annular shoulder 6 of the base is a cylinder 7. This cylinder has diametrically opposite portions removed by milling as shown at 8 and 9 to an extent to penetrate the inner surface of the cylinder.

Fixed to cylinder 7 by means of screws 10 is a cover plate 11, and fixed centrally thereof by means of screws 12 is a washer-like retainer 13 for the spring 14.

Centrally of the cover 11 is a hub-like portion 15 slotted as at 16 forming a sleeve seat for a jacket 17 of the plunger assembly.

Insulation on which the coil 18 is wound consists of a disk 19 resting on the base 1, another disk 20 under the cover plate 11 and a cylindrical part 21 surrounding at its outer extremity the hub 15 and, at its inner extremity, an annular shoulder 22 on the base 1.

10 The plunger assembly consists of a central rod member 23 and jacket members 17 and 24. Jacket 24 is fitted in a counterbore 25 in jacket 17 and each jacket has an internal bore 26 threaded to receive a threaded enlargement 27 on rod 23. Jacket 24 has a flanged head 28, knurled or polygonal and may be turned relative to jacket 17 to lock rod 23 in position. For this purpose, inner jacket 17 is held against rotation by means of pins 29 engaging in slots 16.

20 Transmission of the thrust of plunger rod 23 to the sear 30 is accomplished through the agency of a system of levers comprising a main lever 31 pivoted by a pin 32 in a slot 33 in the base 1, and a trip off lever 34 pivoted near the extremity of lever 31 by a pin 35.

25 Seated in the end of plunger rod 23 is a button headed screw 36 affording tangential contact with face 37 of the lever 31 as the latter swings under urging of the plunger rod 23. This swinging is resisted by a flat spring 38 engaging main lever 31. Both spring 38 and coiled spring 14 held between retainer 13 and flange 28 on outer jacket 24 serve to hold the plunger system normally retracted when the coil 18 is not energized.

30 Trip-off 34 consists of a generally sector-shaped member having thin portions 42 and 43 and intermediate thickened portions 44 forming a pair of shoulders. Thin portion 42 is fitted in a slot 45 in lever 31, and shoulders 44 serve to engage slant portions 46 on the sides of slot 45 to form a stop for the trip-off 34, which is urged to this position by a flat spring 47 retained in the lever 31 by a screw 40.

35 Shown at 48 is a lead-in plug for the wire 49, and attached to the flat portion 8 of cylinder 7 by screws 50 is a housing for the plug socket 51 consisting of a front plate 52 and side plates 53. Socket 51 is in electrical connection with coil 18 and the terminus of the coil is led out through an opening 54 in the cylinder 7 and grounded on the cylinder by means of a screw as at 55.

40 The wire 49 leads to an intermittent contact device functioning from an aircraft engine which is so adjusted as to energize the coil 18 only 50 when an opening between the propeller blades is

in front of the gun. Such a contact device is old in the art and is not here illustrated since it forms no part of the present invention. For the same reason the sear mechanism is not illustrated, it being sufficient for the purposes of the present application to state that a sliding motion of the sear slide 30 will result in release of the firing pin (not shown).

The operation is as follows: Upon energization of the coil, the plunger system 23, 24 and 17 or composite plunger moves inward as a unit compressing spring 14 and forcing lever 31 inward against the pressure of spring 38. This motion is transmitted to sear slide 30 through trip-off 34.

Upon firing, the bolt 56 is thrown rearwardly, carrying with it the sear slide 30, and is then returned to battery position, the sear slide meanwhile being returned to its prefiring position, the position shown in the drawing. During recoil and return of the bolt and sear, the plunger continues to reciprocate under the influence of the springs 14 and 38 and the intermittent energization of the coil.

If the plunger system happens to be drawn inwardly at the time the bolt returns to battery, the returned sear slide will rotate the trip-off 34 against the pressure of its spring 47, thus permitting the bolt to return to full battery position. On the subsequent inward thrust of the plunger, trip-off 34 will have returned to position against step 46 under the urging of spring 47 and the sear slide will be urged inward to fire the next round. Thus, the gun will always fire on the stroke of the plunger next succeeding the full return of the bolt to battery position.

The provision of a coil seated on the base of the trigger motor makes for compactness, and the direct linear action of the plunger on the sear slide speeds up the action. The general fidelity of operation is improved by the adjustment feature on the plunger rod.

We claim:

A trigger motor for an automatic gun, comprising a base having a central opening therein and adapted to be secured to the side plate of a gun, a cylindrical sleeve secured to said base in coaxial relation with said central opening, a cover secured to the end of the cylinder and having a hub-like central portion extending 15 partway into said cylinder, an electromagnetic coil surrounding said cylinder, a plunger reciprocable in said hub-like portion and capable of completing a magnetic circuit to said base when said coil is energized, said plunger comprising a centrally recessed internally threaded portion extending through the hub-like portion, an internally threaded flanged lock nut extending into said centrally recessed portion, a threaded rod engaging the threads of the lock nut and 20 threads of said centrally recessed portion and projecting through the central opening in the base, a centrally apertured retainer secured to said cover for retaining the plunger in the cover, a compression spring interposed between said retainer and lock nut flange, and a means for locking the plunger against rotation in said hub-like portion.

NORMAN K. TURNBULL.
